STORAGE PILE AND METHOD OF
PRODUCING SAMEWalter T. Brown, Hackensack, N. J., assignor to
Bethlehem Steel Company, a corporation of
Pennsylvania

Application May 18, 1939, Serial No. 274,346

8 Claims. (Cl. 44—1)

My invention relates to the storage of coal. More specifically my invention relates to a method of storing coal to prevent oxidation and spontaneous combustion thereof.

It is well known that all coals undergo spontaneous heating in storage, due to oxidation. Such oxidation proceeds slowly with anthracite coals, but is very marked with bituminous coals and is particularly harmful to bituminous coals which are intended to be coked. Only a small amount of oxidation is necessary to destroy the coking properties of low and medium volatile coals, and decrease the yield of their most valuable by-products such as phenols and cresols.

While the extent to which coal will oxidize in storage depends in part upon the nature of the coal itself, it also depends in part on other factors. I have found that the rate of oxidation increases as the size of the coal particles decreases. I have also found that wet or damp coal oxidizes faster than dry coal.

When coal is stored in a pile, oxidation usually first occurs from six to fifteen feet within the pile and travels from there towards the center of the pile. Such oxidation is due primarily to the passage of air currents up through the pile, which currents oxidize the surfaces of the coal particles. Such oxidation causes a rise in the temperature of the coal, which in turn creates a stack effect in the coal pile and causes air to be drawn through the pile in greater quantities so that oxidation proceeds more rapidly. Thus oxidation, once started, is a self-sustaining process.

If oxidation of the coal continues for a sufficiently long time spontaneous combustion of the coal may result. Even if spontaneous combustion does not take place, oxidation has a deleterious effect on the coal, as above stated.

Broadly speaking, my invention comprises arranging the coal to be stored in a plurality of horizontal superimposed layers, each layer being separated from the one beneath it by a substantially air-tight and waterproof cover.

My invention is more fully described in the following specification and shown in the accompanying drawing in which—

Figure 1 is a plan view of a coal pile embodying my invention, and

Figure 2 is a view in vertical section along 50 the line 2—2 of Figure 1.

Referring to the figures, 10 represents a coal pile which is separated into a plurality of layers 11, 12, 13, 14 and 15 by the covers 16, 17, 18, 19 and 20, respectively, each of which envelops 55

the area of the layer immediately beneath it. As shown in the figures the cover enveloping each layer of coal extends over the sides of such layer and may overlap the next lower cover as indicated at 21. This is not absolutely essential, however, since substantial benefits are obtained if the covers merely cover the top surfaces of the layers to which they are applied.

Each cover may be formed of any substantially air-tight material, and preferably comprises a plurality of strips 22 which may be of sisal-kraft paper or other strong material substantially impervious to air and water. As shown at 23, each strip of paper overlaps the adjoining strip and may, if desired, be cemented thereto.

In practising my invention a substantially flat layer of coal is spread on the ground over an area sufficiently large to accommodate the quantity of coal to be stored. The thickness of the layer is not critical, but is preferably less than ten feet. This layer is then preferably compacted with a roller or bulldozer. This has the effect of decreasing the air spaces between the coal particles and also flattens the top surface of the layer so as to render the diaphragm less liable to injury from the sharp corners of the coal. Over this layer of coal a cover of the type hereinabove described is laid. On top of this cover another layer of coal is placed, compacted and covered, as above described, and so on until the pile is completed. Although the flattening and compacting of each layer of coal is desirable, it is not essential, however, in order to obtain the benefits of my invention.

When the coal thus stored is needed for use it is preferably removed layer by layer. If the several covers are made of sisal-kraft paper or the like they may easily be torn away, and are comparatively inexpensive.

It is desirable to cover the top layer of coal 15, as shown in the drawing. This is not essential, however, since comparatively little stack effect and oxidation will take place in a layer of coal of the order of ten feet thick or less. If the top layer is left uncovered, the cover immediately beneath it should preferably be sloped somewhat so that rain water will drain therefrom.

By separating a pile of coal into layers by means of substantially air-tight covers, as above described, the circulation of air through the pile is greatly diminished and oxidation is accordingly prevented. Compacting and flattening each layer, in addition, tends to minimize the

circulation of air, but this is not essential for the successful practice of my invention.

While my invention is particularly useful for the storage of coal, it is not to be limited thereto, since it is equally adapted to the storage of other materials which, when stored in piles in the atmosphere, are subject to oxidation and spontaneous combustion.

Having thus described my invention, what I claim as new and desire to secure by Letters Patent is:

1. The method of storing coal which comprises successively forming portions of the coal to be stored into a plurality of comparatively thin superimposed layers and covering the top and 15 sides of each such layer with a substantially air-tight covering.

2. The method of storing coal which comprises superimposing upon each other comparatively thin layers of the coal to be stored and separating each such layer from the immediately adjacent layers by means of a substantially air-tight covering.

3. The method of storing coal which comprises superimposing upon each other comparatively 20 thin layers of the coal to be stored, compacting

and leveling the surface of each such layer, and separating each such layer from the immediately adjacent layers by means of a substantially air-tight covering.

4. A coal storage pile comprising a plurality of compacted layers of coal superimposed upon each other, each such layer being covered by a substantially air-tight covering.

5. A coal storage pile comprising a plurality of layers of coal superimposed upon each other, each such layer being separated from the immediately adjacent layers by a substantially air-tight covering.

6. A coal storage pile comprising strata of coal and means intermediate the strata for impeding the passage of air through the pile.

7. A coal storage pile comprising comparatively thin, horizontal strata of coal and means intermediate adjacent strata for preventing the passage of air therethrough.

8. A coal storage pile comprising a plurality of comparatively thin, superimposed layers of coal, and a substantially air-tight cover for each of said layers.
